UNITED STATES PATENT OFFICE.

ELLANORA D. LOCHNER, OF BROOKLYN, NEW YORK.

REFRIGERATOR.

1,030,668.

Specification of Letters Patent. Patented June 25, 1912.

Application filed November 30, 1910. Serial No. 594,889.

To all whom it may concern:

Be it known that I, ELLANORA D. LOCHNER, a citizen of the United States, residing at the city of Brooklyn, in the county of 5 Kings and State of New York, have invented new and useful Improvements in Refrigerators, of which the following is a specification.

This invention relates to refrigerators, 10 and its object is to provide a device which stores and suspends the ice in its upper part in a perforated basket and by means of a partition causes a circulation of air down one side and up the other in order to thoroughly distribute the cool air through all 15 parts of the refrigerator as will be more fully described in the following specification, set forth in the claim and illustrated in the drawings, wherein,

20 Figure 1 is a front elevation of the refrigerator partly broken away to show the interior construction. Fig. 2 is a sectional view on the line 2—2 of Fig. 1. Fig. 3 is a sectional view on the line 3—3 of Fig. 1. Fig. 25 4 is a top plan view with the top removed. Fig. 5 is a sectional detail view of one of the doors.

The refrigerator 5 is made of several 30 thicknesses of charred boards which confine the cool air in an odorless condition and keep the interior clean and sanitary. The refrigerator is divided into two compartments at its lower end by means of the removable partitions 6 of sheet metal or any 35 other desired material, with openings 13 and 13' at top and bottom, and above same is a tray 7, supported by cleats on the front and rear walls and which catches the water from the block of ice 8 as it melts, to conduct 40 same through the lower part of the refrigerator to the pan 9 beneath same. For this purpose a waste pipe 10 is provided, which has a trap and leads from the tray 7 to the pan 9, and over the tray 7 is a wire basket 45 11 to contain the block of ice which may be covered by a hood 12 of canvas or rubber cloth to protect the block against melting and evaporation as the warm air from below ascends and is displaced by the falling 50 cold air. The basket 11 is supported by the supporting frames 14' which are suitably mounted in the upper corners of the refrig-

erator. Baskets 15 may be slidingly supported in the frames 14' in any suitable manner and may be used for any desired 55 purpose.

The partition 6 stops a short distance above the bottom of the refrigerator so that openings 13 and 13' are left for the passage of air from one side of the refrigerator to 60 the other, and the cool air from the ice drops on either side of the partition and is permitted to pass through the openings 13' to set up a circulation throughout the refrigerator. Within the refrigerator and on each 65 side of the partitions may be arranged shelves 14 of perforated material or bars and baskets being adapted to allow of the circulation of the air in order to cool their contents, and they are supported by cleats 70 which permit of their instant removal. As will be seen in Fig. 3 the baskets 15 may be slid outward and the shelves made accessible when the doors of the refrigerator are open.

In order to make the refrigerator thoroughly air-proof, and to prevent the admission of warm air, the doors are constructed as will be seen in Fig. 5, where the jambs 16 are faced with a sheet metal lining and the inner faces of the door also provided with a 80 lining 17 to fit against same and make a close joint. In order to insure this joint, the doors are provided with a packing of endless rubber tube 18, held within a socket 19 of the lining of the door, and this tube is 85 adapted to fit against the lining 16 and be compressed against the same by the door in order to prevent the movement of air between the door and jamb.

It is obvious that the parts of this device 90 may be modified or otherwise arranged without departing from the essential features above described.

The interior of the refrigerator may be lined with metal, and it will be seen that all 95 of the parts are removable so that they may be kept perfectly clean and easily replaced.

What I claim as new and desire to secure by Letters Patent is,—

In a refrigerator the combination with a 100 casing, of airtight doors in the lower portion of said casing, supporting frames having sliding baskets therein at the upper corners of the refrigerator, a basket for receiving

ice supported by said supporting frames and
an airtight door for the ice compartment
and a partition with upper and lower open-
ings, and cleats on the front and rear walls
5 of said refrigerator above said partition,
and a tray beneath said ice basket and sup-
ported by said cleats.

In testimony whereof I affix my signature
in presence of two witnesses.

ELLANORA D. LOCHNER.
